UNITED STATES PATENT OFFICE

96,672

DESIGN FOR AN ELECTRIC SIGN

James A. Howenstine, Lima, Ohio, assignor to
Neon Products, Inc., Lima, Ohio, a corporation
of Ohio

Application May 14, 1935, Serial No. 56,827

Term of patent 14 years

To all whom it may concern:

Be it known that I, James A. Howenstine, a citizen of the United States and resident of Lima, in the county of Allen and State of Ohio, have invented a new, original, and ornamental Design for an Electric Sign, of which the following is a specification, reference being had to the accompanying drawing, forming a part thereof.

Figure 1 is a front perspective view of an electric sign embodying the invention, and Fig. 2 is a section thereof on the line 2—2 in Fig. 1.

The dominant feature of my design resides in

the appearance presented by locating a tubular translucent illuminating member adjacent to each of the upper and lower free edges of a glass sign plate, said members being parallel to and substantially coextensive with the respective plate edges.

I claim:

The ornamental design for an electric sign, substantially as shown and described.

In testimony whereof I have hereunto signed my name to this specification.

JAMES A. HOWENSTINE.
